UNITED STATES PATENT OFFICE.

DELL C. DAVISON, OF BETHLEHEM, PENNSYLVANIA.

WRENCH.

1,227,396.

Specification of Letters Patent.

Patented May 22, 1917.

Application filed October 14, 1916. Serial No. 125,660.

To all whom it may concern:

Be it known that I, DELL C. DAVISON, a citizen of the United States, residing at Bethlehem, in the county of Northampton and State of Pennsylvania, have invented new and useful Improvements in Wrenches, of which the following is a specification.

This invention relates to improvements in wrenches, and one of the principal objects 10 of the invention is to produce a simple, cheap and convenient wrench which may be used upon objects of varying sizes and which will automatically adjust itself to grip the said objects.

15 A further object of the invention is to produce a wrench that may be actuated by one hand of the operator, and which when turned in one direction upon an object will grip the said object and when turned in another direction will release the said object so that a substantially rigid movement will be afforded.

Further objects and advantages will be apparent as the nature of the invention is 25 more fully understood, reference being had to the accompanying drawing in which there is illustrated a simple but satisfactory reduction of my improvement to practice, it being understood, however, that the details 30 of construction therein illustrated are subject to such changes in form, construction, etc., as fall within the scope of the appended claim.

In the drawing:

35 Figure 1 is a side elevation of a wrench constructed in accordance with the present invention;

Fig. 2 is a transverse sectional view approximately on the line 2—2 of Fig. 1; and

40 Fig. 3 is a side elevation, partly in section, and parts being broken away.

As disclosed by the drawings, the wrench includes an outer jaw 1 having an angular shank 2, the said shank being preferably rectangular in cross section. The numeral 3 designates the inner jaw which co-acts with the jaw 1, the said jaw having an opening therein through which passes the shank 2 of the jaw 1, and the said jaw 3 is provided 45 with a hollow handle 4 to receive the said shank 2 of the jaw 1. The outer end of the handle 4 is closed, but a portion of the said handle, from the jaw 3 is open upon one of its edges and if desired for a suitable distance 50 upon both of its sides in a line with the first mentioned opening. The opening in the edge

of the handle is designed to permit of access being obtained to a series of transversely arranged teeth 5 provided upon one of the edges of the shank 2, and the openings in 60 the sides of the handle are desirable to permit of the snug engagement with the edges provided by the said openings, of the sides or flanges 6 provided upon a lever 7. This lever, between its sides 6, for a determined 65 distance is provided with transverse teeth 8 that are adapted to co-act with the teeth 5 of the shank 2, and the lever 7 has its inner end provided with a reduced rounded tongue 9 that is adapted to be received in an arcuate 70 slot or depression 10 upon the outer face of the jaw 3, whereby the lever is fulcrumed to the said jaw 3.

The shank 2, from the outer end thereof, is centrally formed with a longitudinally extending bore 11 within which is secured a helical spring 12 that has its outer end, or its end extending through the bore 11 connected, as at 13, to the inner transverse or end wall in the bore of the handle 4. 86

The outer end of the lever 7 is shaped to provide a handle or grip 14, and the numeral 15 designates a flat spring which has one of its ends secured, as at 16, to one of the edges of the handle 4, the opposite end of the 85 said spring 15 being received between the flanges 6 of the lever 7, and being provided with an elongated slot 17. The numerals 18 designate headed members which have their shanks passing through the slot 17 90 and which are secured to the handle or grip 14 of the lever 7. By this arrangement, it will be noted that the lever 7 is normally 95 swung upon its fulcrumed member or tongue member to bring the teeth 8 thereof out of engagement with the teeth 5 of the shank 2, and the limit of the swinging of the said lever is limited by the spring 15, so that the gripping end 14 of the said lever is at all times accessible to the hand of the 100 operator which grasps the handle 4 of the wrench. The spring 12 is of sufficient strength to at all times move the jaws 1 and 3 toward each other, but is not of sufficient strength to prevent the said jaws being 105 separated to receive the object to be operated upon therebetween. When the lever 7 is swung toward the shank 2 to bring the teeth 8 thereof into engagement with the teeth 5 of the said shank, it will be apparent that 110 the jaws 1 and 3 will be held in locked relation with each other, but when pressure

upon the said lever 7 is relieved the spring 15 will swing the lever to bring the teeth 8 thereof out of engagement with the teeth 5 of the shank 2, and when in such position, 5 the jaws connecting with the object operated upon will not engage with the said object with sufficient friction to turn the same but will permit the wrench to turn upon the object, so it will be apparent that the wrench 10 may be permitted to ratchet in one direction upon the said object, and from the above description, taken in connection with the accompanying drawing, the simplicity of the device as well as the advantages 15 thereof will, it is thought, be perfectly apparent to those skilled in the art to which such invention appertains without further detailed description.

Having thus described the invention, what 20 is claimed as new, is:

In a wrench, an outer jaw having an angular toothed shank, an inner jaw having

a hollow handle receiving the shank and having an opening in the sides and in one of the edges thereof to disclose the teeth of the shank, spring means between the handle and shank for normally moving the jaws toward each other, a lever having side flanges and being provided with teeth disposed between the flanges, a rounded tongue upon one of the ends of the lever, the inner jaw having an arcuate depression disposed to loosely receive the tongue of the lever, a flat spring having one of its ends screwed to the handle and its other end provided with a slot, a headed member passing through the slot and engaging with the lever whereby to normally swing the lever to bring the teeth thereof out of engagement with the teeth of the shank and to limit such swinging movement of the lever.

In testimony whereof I affix my signature.
DELL C. DAVISON.
